UNITED STATES PATENT OFFICE.

MATTHIAS REIFF LONGACRE, OF MILLERSTOWN, PENNSYLVANIA.

RAILWAY.

No. 822,745.

Specification of Letters Patent.

Patented June 5, 1906.

Application filed October 30, 1905. Serial No. 284,955.

To all whom it may concern:

Be it known that I, MATTHIAS REIFF LONGACRE, a citizen of the United States, residing at Millerstown, in the county of Perry and State of Pennsylvania, have invented certain new and useful Improvements in Railways, of which the following is a specification.

My invention consists in an improved railway, the road-bed superstructure upon which the rails rest being formed of concrete or cement sills made in sections and firmly secured together by embedded plates and tie-rods, the concrete or cement sills having also embedded therein suitable chairs for securing the rails thereto, which have suitable tie-rods extending laterally from one sill to the opposite sill, forming cross-ties. The sectional sills rest in substantially continuous base portions, formed also of concrete or cement. A suitable cushioning-strip may be interposed between the sills and the base portion, the whole forming a durable and substantially rigid foundation structure for the rails, greatly increasing the efficiency of the railway.

In the accompanying drawings, Figure 1 is a plan view of a portion of my improved railway. Fig. 2 is a side elevation. Fig. 3 is an enlarged cross-sectional view. Fig. 4 is an enlarged longitudinal section on the line 4-4 of Fig. 1. Fig. 5 is a perspective view of one of the sill-sections. Fig. 6 is a perspective view of one of the rail-chairs. Fig. 7 is a perspective view of one of the coupling-plates. Fig. 8 is a perspective view of a portion of the sill-base; and Fig. 9 is a side elevation of one of the sills, showing a modified form of the coupling-rods.

A is the base portion of my improved railway, preferably made of concrete, having the recessed portion a, into which the sectional sills B are placed. The sectional sills B are preferably made of cement and molded into the proper form.

C represents the rail-chairs, suitably shaped to receive the rail and having the extensions c and c'.

D is a clamping-plate secured to the chairs by bolts d, which firmly clamp the rails I in these chairs.

E represents tie-plates, to which tie-rods H are secured. The chairs C and the tie-plates E are molded in the sill-sections B, and the top of the base of the chairs is inset by the re-

cess b in the surface of the sill, so that the base of the rail I rests flush with the surface of the chair and sill.

G represents tie-rods, molded also in the sills and secured to the chairs for coupling the chairs together, forming a firm stiffening connection for the chairs and strengthening the sills.

F represents tie-rods forming cross-ties extending laterally from sill to sill, preferably tapped into the extensions c' of the chairs and having a turnbuckle f therein, so that adjustment is readily obtained in setting the sills for securing alignment of the rails. The end extensions e of the plates E project beyond the sides of the sills sufficiently to receive the bolts H. The ends of the extensions c' of the chairs are set about flush with the inner sides of the sills, so that the cross-ties F may be readily inserted or removed.

J is a suitable cushioning-strip, which may be inserted between the sills and the base portion.

In the modification illustrated in Fig. 9 the rods G extend through the length of the sill and project at one end slightly beyond the sill for the purpose of further strengthening the sill and forming dowel-pins for fitting the adjoining sill.

The sills and base portion when finally set are ballasted, preferably by stone or cinders or suitable material, thus forming a solid concrete and cement road-bed securely bound together and capable of rapid and inexpensive construction.

Having now described my invention, what I claim as new, and desire to secure by Letters Patent, is—

1. A railway having sectional sills for supporting the rails formed of cement or concrete said sectional sills resting in a substantially continuous base portion formed of concrete or cement said sectional sills being suitably tied together.

2. A railway having sectional sills for supporting the rails formed of cement or concrete said sectional sills being tied together by plates embedded in the sills having suitable bolts coupling said plates together.

3. A railway having sectional sills for supporting the rails formed of cement or concrete said sectional sills being tied together by plates embedded in the sills having suitable bolts coupling said plates together, said

sectional sills resting in a substantially continuous base portion formed of concrete or cement.

4. A railway having sectional sills formed of concrete or cement said sectional sills being suitably tied together and having embedded therein suitable chairs for supporting the rails.

5. A railway having sectional sills formed of concrete or cement, said sectional sills being suitably tied together and having embedded therein suitable chairs for supporting the rails, said chairs having lateral adjustable tie-rods, connecting with chairs opposite.

15 6. A railway having sectional sills formed of cement said sectional sills being suitably tied together and having embedded therein suitable chairs for supporting the rails said sectional sills resting in a substantially continuous base portion formed of concrete.

7. A railway having sectional sills formed of cement said sectional sills being suitably tied together and having embedded therein suitable chairs for supporting the rails, said 25 sectional sills resting in a substantially continuous base portion formed of concrete, and a cushioning-strip between the sills and the base portion.

8. A railway having sectional sills formed of concrete or cement said sectional sills being suitably tied together and having embedded therein suitable chairs for supporting the rails said chairs having lateral adjustable tie-rods connecting with chairs opposite and said sectional sills resting in substantially continuous base portions formed of concrete or cement.

9. A railway having sectional cement sills suitably tied together, and having embedded therein suitable chairs for supporting the rails said chairs having lateral adjustable tie-rods connecting with chairs opposite and said sectional sills resting in substantially continuous concrete base portions.

10. A railway having sectional cement or 45 concrete sills suitably tied together and having embedded therein chairs for supporting the rails having rods passing through them and extending the length of the sills, forming dowel-pins at one end of said sills.

In testimony whereof I affix my signature in presence of two witnesses.

MATTHIAS REIFF LONGACRE.
